(57) **ABSTRACT**

An uphole section has a first diameter. A midhole section has a second diameter that is larger than the first diameter. The midhole section is attached to the uphole section prior to installation into a wellbore. A downhole section has a third diameter that is smaller than the second diameter. The downhole section is attached to the midhole section prior to installation into the wellbore.

PRODUCING GAS THROUGH VARIABLE
BORE PRODUCTION TUBING

TECHNICAL FIELD

This disclosure relates to hydrocarbon gas production.

BACKGROUND

Production of hydrocarbon gasses involves forming a wellbore into a geologic formation, and inserting production tubing into the wellbore to a production zone. The production tubing directs the hydrocarbons from the geologic formation towards a topside facility located on a terranean surface. Production tubing often has a monobore or tapered (two section) design. A monobore design includes a same inner diameter from the production zone to the topside facility. Such tubing can be constructed in sections in the field, or can be fabricated offsite and be inserted into the wellbore from spools. Tapered designs include a downhole section coupled to an uphole section. The uphole section has a diameter greater than the downhole section, and the sections are arranged coaxially with an uphole end of the downhole section extending partially into a downhole end of the uphole section.

SUMMARY

This disclosure describes technologies relating to producing gas through variable bore production tubing.

An example of the subject matter described within this disclosure is a prefabricated production tubing string with the following features. An uphole section has a first diameter. A midhole section has a second diameter that is larger than the first diameter. The midhole section is attached to the uphole section prior to installation into a wellbore. A downhole section has a third diameter that is smaller than the second diameter. The downhole section is attached to the midhole section prior to installation into the wellbore.

Aspects of the example prefabricated production tubing string, which can be combined with the example prefabricated production tubing string alone or in combination with other aspects, include the following. The first diameter and the third diameter are substantially equal.

Aspects of the example prefabricated production tubing string, which can be combined with the example prefabricated production tubing string alone or in combination with other aspects, include the following. The first diameter is greater than the third diameter.

Aspects of the example prefabricated production tubing string, which can be combined with the example prefabricated production tubing string alone or in combination with other aspects, include the following. A first transition is between the uphole section and the midhole section. The first transition includes a first end coupled to the uphole section and a second end coupled to the midhole section. The first end has a diameter substantially the same as the uphole section and the second end having a diameter substantially the same as the midhole section. A second transition is between the midhole section and the downhole section. The transition includes a first end coupled to the midhole section and a second end coupled to the downhole section. The first end has a diameter substantially the same as the midhole section. The second end has a diameter substantially similar to the downhole section.

Aspects of the example prefabricated production tubing string, which can be combined with the example prefabricated production tubing string alone or in combination with other aspects, include the following. The first transition is between the uphole section and the midhole section. The first end has a diameter substantially the same as the uphole section and the second end has a diameter substantially the same as the midhole section. A second transition is between the midhole section and the downhole section.

2

cated production tubing string alone or in combination with other aspects, include the following. The first transition and the second transition include a corrosion or erosion resistant alloy.

- 5 Aspects of the example prefabricated production tubing string, which can be combined with the example prefabricated production tubing string alone or in combination with other aspects, include the following. The uphole section is substantially 10% of a total length of the tubing string.
- 10 Aspects of the example prefabricated production tubing string, which can be combined with the example prefabricated production tubing string alone or in combination with other aspects, include the following. The midhole section is substantially 75% of a total length of the tubing string.
- 15 Aspects of the example prefabricated production tubing string, which can be combined with the example prefabricated production tubing string alone or in combination with other aspects, include the following. The downhole section is substantially 15% of a total length of the tubing string.
- 20 An example of the subject matter described within this disclosure is a method with the following features. Gas is produced through production tubing. The production tubing includes an uphole section having a first diameter. A midhole section has a second diameter that is larger than the first diameter. A downhole section has a third diameter that is smaller than the second diameter.
- 25 Aspects of the example method, which can be combined with the example method alone or in combination with other aspects, include the following. A production rate of the gas exceeds 300 million standard cubic feet of gas per day.
- 30 Aspects of the example method, which can be combined with the example method alone or in combination with other aspects, include the following. A pressure of the production gas exceeds 10,000 pounds per square inch.
- 35 Aspects of the example method, which can be combined with the example method alone or in combination with other aspects, include the following. The production gas comprises sour production gas.
- 40 An example of the subject matter described within this disclosure is a production system with the following features. A production string is within the wellbore. The production string includes an uphole section having a first diameter. A midhole section has a second diameter that is larger than the first diameter. A downhole section has a third diameter that is smaller than the second diameter.
- 45 Aspects of the example production system, which can be combined with the example production system alone or in combination with other aspects, include the following. The wellbore is a deviated or horizontal wellbore.
- 50 Aspects of the example production system, which can be combined with the example production system alone or in combination with other aspects, include the following. The first diameter and the third diameter are substantially equal.
- 55 Aspects of the example production system, which can be combined with the example production system alone or in combination with other aspects, include the following. The first diameter is less than the third diameter.
- 60 Aspects of the example production system, which can be combined with the example production system alone or in combination with other aspects, include the following. A first transition is between the uphole section and the midhole section. The first transition includes a first end coupled to the uphole section and a second end coupled to the midhole section. The first end has a diameter substantially the same as the uphole section and the second end has a diameter substantially the same as the midhole section.
- 65 Aspects of the example production system, which can be combined with the example production system alone or in combination with other aspects, include the following. A second transition is between the midhole section and the downhole section.

section. The transition includes a first end coupled to the midhole section and a second end coupled to the downhole section. The first end has a diameter substantially the same as the midhole section. The second end has a diameter substantially similar to the downhole section.

Aspects of the example production system, which can be combined with the example production system alone or in combination with other aspects, include the following. The first transition and the second transition include a corrosion or erosion resistant alloy.

Aspects of the example production system, which can be combined with the example production system alone or in combination with other aspects, include the following. The uphole section is substantially 10% of a total length of the production string.

Aspects of the example production system, which can be combined with the example production system alone or in combination with other aspects, include the following. The midhole section is substantially 75% of a total length of the production string.

Aspects of the example production system, which can be combined with the example production system alone or in combination with other aspects, include the following. The downhole section is substantially 15% of a total length of the production string.

Particular implementations of the subject matter described in this disclosure can be implemented so as to realize one or more of the following advantages. The concepts described herein allow for resilient, high-flow, high-pressure sour or sweet gas production.

The details of one or more implementations of the subject matter described in this disclosure are set forth in the accompanying drawings and the description below. Other features, aspects, and advantages of the subject matter will become apparent from the description, the drawings, and the claims.

BRIEF DESCRIPTION OF THE DRAWINGS

FIG. 1 is a schematic view of an example production wellbore with production tubing.

FIG. 2 is a flowchart of an example method that can be used with aspects of this disclosure.

Like reference numbers and designations in the various drawings indicate like elements.

DETAILED DESCRIPTION

This disclosure relates to production tubing capable of producing ultra-high rate, sour gas with lower erosion in high-pressure, high-temperature, sour carbonate or clastic reservoirs when compared to conventional production tubing. The resulting production tubing has three varying diameter sections, an uphole section with length determined by a combination of hydrate and erosion risk tendency, a midhole section with length determined by optimal production rate and installation requirements, and a downhole section determined by mechanical strength required to ensure production for a given reservoir condition. The ultra-high rate wells are classed as wells with a production rate above 300 million standard cubic feet per day.

FIG. 1 is a schematic view of an example production wellbore 100 with production tubing 102 installed. In some implementations, the production tubing is designed and fabricated prior to being installed within the wellbore. That is, the production tubing can be produced and built off-site or on-site, but is fully constructed to a substantially full

length (for example, 90%) prior to installation. The prefabricated tubing string includes three sections: an uphole section 104, a midhole section 106, and a downhole section 108. The uphole section 104 has a first diameter. The midhole section 106 is attached to a downhole end of the uphole section 104 prior to the production tubing's installation into the wellbore 100. The midhole section 106 has a diameter that is larger than the diameter of the uphole section 104. The downhole section 108 has a third diameter that is smaller than the second diameter. The downhole section 108 is attached to the midhole section 106 prior to installation into the wellbore 100. While the illustrated implementation shows the production tubing 102 installed within a vertical wellbore, the concepts described herein are similarly applicable to deviated and horizontal wellbores.

At an uphole end of the production tubing 102 is a subsurface valve 110. The subsurface valve 110 is used to control the wellbore 100, more specifically, to shut-in the wellbore. In some implementations, the subsurface valve 110 is controlled from a topside facility (not shown). The subsurface valve 110 is made of materials suited for the wellbore environment. In some implementations, the subsurface valve 110 is made of a corrosion or erosion resistant alloy. For example, in implementations with sour gas production, a national Association of Corrosion Engineers (NACE) certified (or similar) valve is used. In some implementations, the bore size of the subsurface valve 110 is determined by iterative flow assurance models.

At a downhole end of the production tubing 102 is a production zone 112. The production zone 112 is fluidically connected to an inner bore of the production tubing 102 by perforations 114. An annulus 116, defined by an outer surface of the production tubing 102 and an inner surface of the wellbore 100, is isolated from production fluids by a packer 118. While illustrated with a single packer 118, multiple packers can be used without departing from this disclosure. In some implementations, additional wellbore components, such as a hanger, can be used in addition to the concepts described herein without departing from this disclosure.

The geometry of each section is dependent upon design considerations such as flow-rate, pressure, and composition of the production stream. For example, in some implementations, the first diameter and the third diameter are substantially equal (within manufacturing tolerances). In some implementations, the first diameter is greater than the third diameter. In some implementations, the first diameter is less than the third diameter. Determining a diameter of one or more sections is done, in some instances, with iterative flow assurance models. In some implementations, the diameter of one or more sections is determined.

The length of each section is similarly dependent upon design considerations such as flow-rate, pressure, and composition of the production stream. Determining a length of each section is done, in some instances, with iterative flow assurance models.

Alternatively or in addition, a length of the uphole section 104 is determined by a combination of hydrate and erosion risk tendencies. Alternatively or in addition, a length of the midhole section 106 is determined by optimal production rate and installation requirements. Alternatively or in addition, a length of the downhole section 108 is determined by mechanical strength required to ensure production for a given reservoir condition. In some implementations, the uphole section 104 is substantially 10% of a total length of the production tubing 102 (plus or minus 5% of the total length of the 102). In some implementations, the midhole

section 106 is substantially 75% of a total length of the production tubing 102 (plus or minus 10% of the total length of the production tubing 102). In some implementations, the downhole section 108 is substantially 15% of a total length of the production tubing 102 (plus or minus 10% of the total length of the production tubing 102).

Between each section is a transition. A first, upper transition 120 is between the uphole section 104 and the midhole section 106. The upper transition 120 includes a first end coupled to the uphole section 104 and a second end coupled to the midhole section 106. The first end of the upper transition 120 has a diameter substantially the same as the uphole section 104, and the second end of the upper transition 120 has a diameter substantially the same as the midhole section 106. A second, lower transition 122 is between the midhole section 106 and the downhole section 108. The lower transition 122 includes a first end coupled to the midhole section 106 and a second end coupled to the downhole section 108. The first end of the lower transition 122 has a diameter substantially the same as the midhole section 106, and the second end of the lower transition has a diameter substantially similar to the downhole section 108.

In some implementations, all or part of the production string is made of a corrosion or erosion resistant alloy. For example, in some implementations, the upper transition 120 and the lower transition 122 are made of an erosion resistant alloy as the reduction in flow diameter can result in particulate impacts upon the transition. In some implementations, such as with sweet (High CO₂ content) or sour (high H₂S content) gasses are produced, an entirety of the string is made of a corrosion resistant alloy.

FIG. 2 is a flowchart of an example method 200 that can be used with aspects of this disclosure. At 202, a string of production tubing 102 is designed with the three sections described throughout this disclosure. The production tubing 102 is constructed, and at 204, the production tubing is received by the wellbore 100. At 206, hydrocarbon gas is produced through production tubing. In some implementations, a production rate of the gas exceeds 300 million standard cubic feet of gas per day. In some implementations, the production gas has a pressure equal to or in excess of 10,000 pounds per square inch. In some implementations, the production gas includes sweet or sour production gas.

While this disclosure contains many specific implementation details, these should not be construed as limitations on the scope of any inventions or of what may be claimed, but rather as descriptions of features specific to particular implementations of particular inventions. Certain features that are described in this disclosure in the context of separate implementations can also be implemented in combination in a single implementation. Conversely, various features that are described in the context of a single implementation can also be implemented in multiple implementations separately or in any suitable subcombination. Moreover, although features may be described above as acting in certain combinations and even initially claimed as such, one or more features from a claimed combination can in some cases be excised from the combination, and the claimed combination may be directed to a subcombination or variation of a subcombination.

Similarly, while operations are depicted in the drawings in a particular order, this should not be understood as requiring that such operations be performed in the particular order shown or in sequential order, or that all illustrated operations be performed, to achieve desirable results. Moreover, the separation of various system components in the implementations described above should not be understood as requiring

such separation in all implementations, and it should be understood that the described components and systems can generally be integrated together in a single product or packaged into multiple software products.

Thus, particular implementations of the subject matter have been described. Other implementations are within the scope of the following claims. In some cases, the actions recited in the claims can be performed in a different order and still achieve desirable results. In addition, the processes depicted in the accompanying figures do not necessarily require the particular order shown, or sequential order, to achieve desirable results.

What is claimed is:

1. A prefabricated production tubing string comprising: an uphole section having a first diameter, the uphole section designed based on a combination of hydrate and erosion tendencies within a well in which the prefabricated production tubing string is to be installed; a midhole section having a second diameter that is larger than the first diameter, the midhole section attached to the uphole section prior to installation into a well, the midhole section designed based on optimal production rate and installation requires of the well, wherein the midhole section is substantially 75% of a total length of the tubing string; and a downhole section having a third diameter that is smaller than the second diameter, the downhole section being attached to the midhole section prior to installation into the well, the downhole section designed based on mechanical strength of the well.
2. The production tubing string of claim 1, wherein the first diameter and the third diameter are substantially equal.
3. The production string of claim 1, wherein the first diameter is greater than the third diameter.
4. The production string of claim 1, further comprising: a first transition between the uphole section and the midhole section, the first transition comprising a first end coupled to the uphole section and a second end coupled to the midhole section, the first end having a diameter substantially the same as the uphole section and the second end having a diameter substantially the same as the midhole section; and a second transition between the midhole section and the downhole section, the transition comprising a first end coupled to the midhole section and a second end coupled to the downhole section, the first end having a diameter substantially the same as the midhole section, the second end having a diameter substantially similar to the downhole section.
5. The production string of claim 4, wherein the first transition and the second transition comprise a corrosion or erosion resistant alloy.
6. The production string of claim 1, wherein the uphole section is substantially 10% of a total length of the tubing string.
7. The production string of claim 1, wherein the downhole section is substantially 15% of a total length of the tubing string.
8. A method comprising:
60 designing an uphole section of a production tubing string based on a combination of hydrate and erosion tendencies within a well in which the production tubing string is to be installed, the uphole section having a first diameter;
designing a midhole section of the production tubing string based on optimal production rate and installation requires of the well;

designing a downhole section of the production tubing string based on mechanical strength of the well; fabricating the production string having the designed uphole section, the designed midhole section and the designed downhole section; producing gas through the production tubing string, the production tubing string comprising:

- the uphole section having the first diameter;
- the midhole section having a second diameter that is larger than the first diameter; and
- the downhole section having a third diameter that is smaller than the second diameter.

9. The method of claim 8, wherein a production rate of the gas exceeds 300 million standard cubic feet of gas per day. 15

10. The method of claim 8, wherein a pressure of the production gas exceeds 10,000 pounds per square inch. 15

11. The method of claim 8, wherein the production gas comprises sour production gas.

12. A production system comprising:

a well;

a production string within the well, the production string comprising:

an uphole section having a first diameter, the uphole section designed based on a combination of hydrate and erosion tendencies within a well in which the prefabricated production tubing string is to be installed;

a midhole section having a second diameter that is larger than the first diameter, the midhole section designed based on optimal production rate and installation requires of the well, wherein the midhole section is substantially 75% of a total length of the production string; and

a downhole section having a third diameter that is smaller than the second diameter, the downhole section designed based on mechanical strength of the well.

5 13. The production system of claim 12, wherein the well is a deviated or horizontal well.

14. The production system of claim 12, wherein the first diameter and the third diameter are substantially equal.

15. The production system of claim 12, wherein the first diameter is less than the third diameter.

10 16. The production system of claim 12, further comprising:

a first transition between the uphole section and the midhole section, the first transition comprising a first end coupled to the uphole section and a second end coupled to the midhole section, the first end having a diameter substantially the same as the uphole section and the second end having a diameter substantially the same as the midhole section; and

a second transition between the midhole section and the downhole section, the transition comprising a first end coupled to the midhole section and a second end coupled to the downhole section, the first end having a diameter substantially the same as the midhole section, the second end having a diameter substantially similar to the downhole section.

17. The production system of claim 16, wherein the first transition and the second transition comprise a corrosion or erosion resistant alloy.

18. The production string of claim 16, wherein the uphole section is substantially 10% of a total length of the production string.

19. The production string of claim 16, wherein the downhole section is substantially 15% of a total length of the production string.
